CLAIM

The ornamental design for a plastic container, as shown and described.

DESCRIPTION

FIG. 1 is a front perspective view of a plastic container showing my new design;

FIG. 2 is a right side view and left side view thereof;

FIG. 3 is a front view and back view thereof;

FIG. 4 is a top view thereof; and,

FIG. 5 is a bottom view thereof.

The elements depicted in broken line segments of equal length form no part of the claimed design. The elements depicted in broken line segments of varying lengths illustrate the extent of the claimed design.
